[57] CLAIM

The ornamental design for a portion of an electronic computer, as shown and described.

DESCRIPTION

FIG. 1 is a top, front and right side perspective view of a portion of an electronic computer showing my new design; FIG. 2 is a front elevational view thereof; FIG. 3 is a top plan view thereof; FIG. 4 is a bottom plan view thereof; FIG. 5 is a right side elevational view thereof; FIG. 6 is a left side elevational view thereof; FIG. 7 is a rear elevational view thereof; and, FIG. 8 is a top plan view with a lid in a closed position. The broken line showing of the remainder of the electronic computer is for illustrative purposes only and forms no part of the claimed design.
